UNITED STATES PATENT OFFICE.

HASCAL A. HOGEL, OF NEW YORK, N. Y.

PROCESS OF CONDENSING FUMES.

No. 927,241.

Specification of Letters Patent.

Patented July 6, 1908.

Application filed July 27, 1905. Serial No. 271,471.

To all whom it may concern:

Be it known that I, HASCAL A. HOGEL, a citizen of the United States, residing at New York, in the county of New York and State 5 of New York, have invented certain new and useful Improvements in Processes of Condensing Fumes; and I do hereby declare the following to be a full, clear, and exact description of the invention, such as will enable 10 others skilled in the art to which it appertains to make and use the same.

My invention relates to improvements in processes of condensing fumes, and is primarily designed for use in connection with 15 the treatment of refractory ores, more especially those containing sulfids of copper, lead, silver and gold. These ores are roasted and volatilized by the combined action of heat, sulfur, oxygen and salt, as set forth in a companion application of even date herewith, Serial No. 271469, renewed April 20, 1908, as Serial No. 428142; and again renewed November 23, 1908, as Serial No. 464,080. The chlorids so produced, mixed with some 20 impurities pass over into the condenser forming the subject matter of another application, Serial No. 271470 and are then condensed, the gold being recovered as the pure metal, the silver as solid chlorid of silver, the copper 25 in solution as a chlorid, or a sulfate and the lead as solid sulfate of lead, the last named compounds being easily reducible, producing the pure metals, silver, copper and lead.

It is well known that many chlorids can be 30 volatilized quite easily, and many attempts have been made to utilize this fact to recover metals from refractory ores, but, so far as I know, all such efforts have been either practical failures, when attempted to be carried 35 out on a commercial scale, or else attended with so much expense as to be prohibited from use. One reason for these failures and the chief one, in my opinion, was the impossibility of obtaining suitable methods and 40 apparatus for condensing the volatilized fumes, and by my present invention this point is most carefully provided for.

In the accompanying drawing, which 45 shows an apparatus adapted to carry out my improved process—Figure 1 is a side elevation, partly broken away, of the condenser, and Fig. 2 is a horizontal cross section, on an enlarged scale, of one of the aspirators.

28 represents the delivery pipe from a volatilizing furnace. Any form of volatilizing furnace may be used, but I prefer the one

shown in the companion application above referred to. This pipe is connected with the tubes 66 of a boiler 65, which tubes are comparatively large. The fumes as they pass 60 through the pipe 28 are at a high temperature, often up to 1800° F. or more, and this heat is utilized to generate steam in the boiler, which may be used for any desired purpose, such as revolving the volatilizing 65 furnace, for example. This preliminary cooling, which, however, must not be allowed to proceed far enough to permit any of the volatilized products to be condensed in the boiler, also lightens the work of the main 70 condenser.

At the exit end of the boiler tubes 66 and communicating therewith is a pipe 28^a and opposite to this pipe is a smaller pipe 30, which pipe passes through a number of aspirators 31. These aspirators are shown in horizontal section in Fig. 2 and are of the type described in my former patent, No. 671,380. Water under pressure is forced in 75 through the pipe 32 into the space 33. Thence the water passes through a narrow 80 opening 34 into a gradually expanding throat 35, which throat is provided inside the case of the aspirator with numerous perforations 36. The opening 34 is controlled by means 85 of the needle valve 37 operated by a hand wheel 38. Each aspirator casing is connected with the pipe 28 by a cross pipe 39. The effect of the swiftly rushing current of water 90 through the opening 34 and throat 35 is to 95 entrain along with it the volatilized materials which are delivered from the pipe 28 and also draw up the liquid which is in the pipe 30, as hereinafter described, and which is connected to the aspirator casing. In Fig. 1, I have shown four of these aspirators, 100 although any desired number may be used. The effect of these aspirators is to cause a partial vacuum in the pipe 28, which aids in the ready discharge of the volatilized material 105 from the furnaces, this operation being also aided by the air pressure in said furnaces, as described in my companion application already referred to. The throats 35 of the aspirators connect with a vertical pipe 40 closed at the top which pipe enters the top 110 of a condensing vessel 41 which is provided with a partition 42 which reaches to the top and nearly to the bottom thereof. Under the influence of the currents produced by the aspirators, the liquid flows up through the pipe 30, mingles with the volatilized ma-

terials coming over through the pipe 28, and is discharged into the condenser 41 which is usually kept pretty nearly full of liquid. The condenser 41 is provided with the usual gage 5 glass 43 connected by valved pipes 44 and 45 with the body of the condenser. The liquid from the pipe 40 charged with the volatilized material and also with air passes down under the partition 41 and up again to the discharge pipe 46 which is connected with a second condensing cylinder 47.

In order to permit the excess of air which comes down through the pipe 40 to escape, I provide an upwardly extending pipe 48 which 15 runs into a casing 49 provided with a stop cock 50 and escape pipe 51. In the casing 49, the pipe 48 dips below the surface of the water contained therein, thus affording a water seal which permits the air to escape 20 freely but prevents a return movement of air through the pipe 48.

The vessel or tank 47 is provided with a liquid discharge pipe 52 which is connected with a rotary or centrifugal pump 53, 25 although any desired type of pump may be used. The liquid is forced by the pump 53 up through the pipe 54 which is closed at the top, and then across through a number of pipes 55 into the pipe 56 which is also closed 30 at the top. While passing through the pipes 55, the liquid is cooled by means of a shower of water discharged through perforations in the pipe 57 which runs above and parallel to the pipes 55, like an ordinary beer cooler. 35 The liquid then passes from the pipe 56 into the pump 62 and back again into the pipe 30. The repeated circulation of the liquid through the condensing apparatus is for the purpose of more completely saturating it, 40 for example, with the soluble chlorid and sulfate of copper.

When the apparatus begins to run, the first portion of the liquid is of course a very dilute solution—so dilute that it would 45 hardly pay to treat it, but after the liquid has been more thoroughly saturated, it reaches a point where it may profitably be treated. The liquid is then drawn out 50 through the pipe 63 provided with a valve 64 from the pipe 56. Through the pipe 58 provided with a valve 59 at the bottom of the tank 47 is discharged a deposit of solid chlorid of silver and a solid chlorid and sulfate of lead. These precipitates are then separated 55 from the liquor that passes over with them in any suitable way, and the liquor is mixed with the liquor which is discharged through the pipe 63. This liquor is then treated in the usual way, as by electrolysis or the insertion of iron therein, to recover the copper. The metallic silver is recovered from the chlorid of silver in the usual way, as by treatment with zinc, and the lead is smelted, producing metallic lead, which usually carries a greater or less percentage of silver and gold 60

which are recovered in the usual way. The gold is recovered in the metallic state for the reason that the compounds of gold which are formed in the operation, namely, the chlorid and a small proportion of the sulfid, are very 70 easily decomposed so that the gold is recovered from the condensing apparatus as a metal. Some of the gold settles in the bottom of the tank 41 which is therefore provided with a discharge pipe 60 having a stop 75 cock 61. Some of it goes over into the second tank 47 and is discharged through the pipe 58, being separated from the lead and silver compounds in the usual way. It will thus be seen that practically all the lead, 80 copper, gold, and silver volatilized in the furnace, is condensed and collected in the condenser, the result being the saving of practically all these metals at a slight expense. If the ore contains zinc this may 85 be practically eliminated during the roasting operation, and the zinc may be recovered or thrown away. If the ore contains iron, this iron will not usually be volatilized, but will remain behind in the furnace either 90 in the form of fine metallic iron or else as a magnetic oxid, and in either case the iron can be recovered in the usual way. Many ores, however, contain too small percentages 95 of iron and zinc to warrant the saving of these metals, especially in localities where labor, fuel, etc., are high, as is the case in many localities where these complex refractory sulfid ores occur. If the ores do contain iron or zinc, these metals are either 100 saved or thrown away, as circumstances dictate.

I claim:—

1. In the treatment of refractory ores, the process of condensing the compounds driven off from said ores by heat, which consists in simultaneously and intimately mixing said volatilized compounds with air and water, causing the water to repeatedly circulate through a condensing apparatus, allowing the excess of air to escape from the water during its passage through the condensing apparatus, and cooling the water during its passage through said condensing apparatus, substantially as described. 115

2. In the treatment of refractory ores, the process of condensing the compounds driven off from said ores by heat, which consists in subjecting the volatilized product to a preliminary cooling, simultaneously and intimately 120 mixing said volatilized product with air and water, causing the water to repeatedly circulate through the condenser, allowing the excess of air to escape from the water during its passage through the condenser and cooling the water during said passage, substantially as described. 125

3. In the treatment of refractory ores, the process of condensing the compounds driven off from said ores by heat, which consists in 130

subjecting said compounds to a preliminary cooling, entraining said compounds and water together by a strong air blast, causing the water to repeatedly circulate through a condenser, allowing the excess of air to escape from the water during its passage through the condenser, cooling the water during said passage and finally collecting the solid and liquid products from the condenser and obtaining the metals therefrom in the usual way, substantially as described.

4. In the treatment of refractory ores, the process of condensing the compounds driven off from said ores by heat, which consists in subjecting said compounds to a preliminary cooling, entraining said compounds and

water together by a strong air blast, causing the water to repeatedly circulate through a condenser, allowing the excess of air to escape from the water during its passage through the condenser, cooling the water during said passage and finally collecting the solid and liquid products from the condenser and obtaining the metals therefrom in the usual way, substantially as described. 25

In testimony whereof, I affix my signature, in presence of two witnesses.
